UNITED STATES PATENT OFFICE.

WILLIAM REGINALD RIDINGS, OF STRETFORD, ENGLAND, ASSIGNOR TO
WESTINGHOUSE ELECTRIC & MANUFACTURING COMPANY, A CORPO-
RATION OF PENNSYLVANIA.

ELECTRIC-ARC LAMP.

No. 805,322.

Specification of Letters Patent.

Patented Nov. 21, 1905.

Application filed March 1, 1904. Serial No. 196,036.

To all whom it may concern:

Be it known that I, WILLIAM REGINALD RIDINGS, a subject of the King of Great Britain, and a resident of Stretford, county of Lancaster, England, have invented certain new and useful Improvements in Arc-Lamps, of which the following is a specification.

This invention relates to electric-arc lamps.

One object of this invention is to provide means whereby a plurality of carbons or electrodes deposited in a lamp can be automatically fed one after the other into the carbon-holders by gravity, so as to maintain a continuous supply of carbons in the holders until the number of carbons deposited has been exhausted. For this purpose, according to this invention, each carbon-holder of a lamp is provided with a magazine into which the respective carbons can be conveniently dropped, say, from the top of the lamp. The magazines are arranged so as to be capable of rotation about an axis parallel with that of the respective carbon-holders and are provided with a convenient number of annularly-disposed longitudinal chambers or longitudinal series of supports capable of freely supporting each carbon practically parallel to the axis of the magazine, so that when a partial rotation is periodically given to the magazine the chambers in succession come into line with the holders. Means are provided whereby the aforesaid periodical partial rotation is automatically given to the magazine so soon as the top end of the carbon in use has been lowered by the feeding-gear below the level of the bottom of the magazine and is completed when the carbon in use has been further lowered to or below the level of the top of the carbon-holder, thus bringing a fresh carbon first into contact with and finally into line with the remainder of the carbon in the holder. As the carbon in the holder is further lowered the aforesaid fresh carbon follows by gravity until it comes within the control of the feeding-gear. This action is repeated until the supply in the magazine is exhausted.

One convenient manner of obtaining the above-mentioned periodical partial rotation of the magazine is to utilize the motion of the feeding or striking gears or that of the solenoid-core which actuates them to revolve a slotted disk or retract a pawl, trigger, pivoted lever, or the like against the resistance

of a spring, so as to bring pressure to bear in the direction of rotation of the magazine against a projecting end of each of the carbons in succession or against a series of projections on the magazine itself. The pressure thus placed on the magazine directly or indirectly tends to retain the carbon in use in contact with the carbon-holder, which provides a counter resistance to the above-mentioned spring. This counter resistance is removed as soon as the feed removes the upper end of the carbon in use from the magazine, allowing the magazine to be partially rotated by the spring bringing the next succeeding carbon first into contact with and then into line with the carbon in the holder. The above-mentioned slotted disk, pawl, trigger, pivoted lever, or the like is thereupon again retracted by the motion of the actuating-gear above mentioned with a like result. It is necessary to provide the gear connecting the actuating mechanism with the aforesaid magazine-rotating device with a lost motion, so as not to interfere with the normal working of the feed or striking gear.

In the accompanying drawings the invention is illustrated by way of example only as applied to lamps of that kind in which the electrodes are inclined with reference to each other and are provided with a magnet for controlling the shape and position of the arc.

Figures 1 and 2 are side elevations at right angles to each other of a lamp constructed in accordance with this invention, the outer casting being removed. Fig. 3 is a sectional plan of the lamp shown in Figs. 1 and 2 drawn to an enlarged scale. Fig. 4 is a detail view, in side elevation and partly in section, showing the connection between the magazines and the carbon-holders; and Fig. 5 is a sectional plan of the same, showing a magazine-rotating device in its normal position. Fig. 6 is a similar view showing the same device in its operative position. Fig. 7 is a view, mainly diagrammatic, showing the arrangement of the electrical circuits of the lamp.

Referring to Figs. 1 to 6, each carbon-holder 1 of the lamp is provided with a magazine 2, into which the respective carbons are dropped, say from the top 3 of the lamp, which is provided for that purpose with suitable openings covered by caps 4, having bayonet-joints 5 or other suitable devices for retaining them

in position. The magazines 22 are so arranged as to be capable of rotating about an axis parallel with that of the respective carbon-holders. This axis may conveniently consist of a 5 rod or tube 6, supported at its lower end in a nut 7 on the carbon-holder 1, (see Fig. 4,) the upper end being suitably supported in the top 3 of the lamp. The magazines 2 are of suitable length to support the carbons practically 10 parallel to the axes of the magazines and are provided with a convenient number, say five, as shown, of annularly-disposed chambers 8. The chambers 8 may be formed, for example, by a number of tubes 9, connected together 15 in any suitable manner, provided with one or more central bearings 10 for the rod 6, the lower end of which bearing or bearings may also serve as a step-bearing to carry the weight of the magazine. The radius of the ring of 20 chambers 8 is equal or approximately equal to the distance between the center of the rod 6 and the center of the corresponding carbon-holder 1, (see Figs. 4, 5, and 6,) so that when a partial rotation is periodically given to the 25 magazine 2 the chambers 8 come in succession into line with the carbon-holder 1. The first carbon 20 to be used on being dropped into the corresponding magazine 2 may pass into the carbon-holder 1, as shown in Fig. 4. The 30 carbon 21, next in rotation to be used on being dropped into the magazine, falls upon a magazine-rotating device 13, hereinafter to be described. The remainder of the carbons are supported vertically by a supplementary 35 table 12. In order to insure when the magazine is filled that one of the carbons inserted shall be in line with the carbon-holder, the openings in the top of the lamp are each provided with a fixed guide-plate (not shown) 40 having a number of holes corresponding to the magazine-chambers and so adjusted that one of the said holes corresponds with the carbon-holder. A periodical partial rotation of the magazines 2 is automatically and conveniently obtained by means of the rotating 45 devices 13, each of which consists of a pawl or trigger pivoted on the rod 6 and preferably operating in the same direction, as shown by the arrows in Fig. 6. One end 14 50 of the said pawls is made sufficiently long to bear against the carbons—for example, carbon 20—and sufficiently broad to support in its normal position the point of the carbon—for example, carbon 21—next in rotation to 55 that carbon against which it happens to bear, as shown in Fig. 5. The ends 14 of the aforesaid pawls in their retracted positions (see Fig. 6) are retained in contact with the carbons by adjustable springs 16, (see Figs. 2 60 and 3,) operating on preferably adjustable connecting-rods 17, pivoted at 18 to the pawls. The pressure thus placed on the carbon 21, and thereby on the magazine, tends to retain the carbon 20, which is partly within the 65 magazine and partly within the holder, in

contact with the latter, which provides a counter resistance to the influence of the corresponding spring 16. The influence of the spring is adjusted so as to cause the pawl to revolve about its center through an arc corresponding to the pitch of the carbon-magazine chambers 8 so soon as the aforesaid counter resistance is removed by the feed mechanism withdrawing from the magazine the top end of the carbon 20 in the holder 1. By this motion the next succeeding carbon 21 is brought first into contact with the top end of the carbon 20 in use and then is brought into line therewith on the carbon 20 being further lowered to or below the level of the top of the carbon-holder 1. Preferably the next succeeding carbon is not brought into line with that in use until the top end of the latter is well below the top of the carbon-holder. By this arrangement all possibility of the spring 16, say by 85 defective adjustment, causing the next succeeding carbon to revolve past the mouth of the carbon-holder is avoided, as the point of the carbon striking the mouth of the holder would constitute an automatic stop. For this purpose the mouths of the carbon-holders are beveled on the advance side at 63, (see Figs. 3 and 6,) so as to allow the point of the next succeeding carbon 21 to fall below the general level of the mouth of the carbon-holder before arriving in alignment therewith. The normal position of the pawls 13 is shown in Fig. 5, and the said pawls are retracted against the resistance of the springs 16 into the position shown in Fig. 6 by gearing connected to the spindle 23 of the striker 24. This gearing consists of a lever 22, keyed on the striker-spindle 23, which when operated by the solenoids 30 causes the said lever to be moved so as to strike the end 14 of the pawl 105 (shown on the left hand of Figs. 3, 4, and 6) or a downwardly-projecting pin 25 secured thereto, and it also serves to operate by means of a pivoted slotted link 26 the end 15 of the pawl. (Shown on the right hand of the right 110 hand of the same figures.) The connection between the pawl end 15 and the slotted link 26 consists of a pin 27, carrying a roller 28, (indicated by broken lines in Figs. 3, 5, and 6,) which takes into the slot of the link 26. The 115 slot in the link 26 provides a lost motion, whereby the striker-spindle 23 is allowed free play at all times. The stroke of the lever 22 and the length of the slot in the link 26 are, however, so arranged as to momentarily relieve the carbons 20 in the holders of the pressure of the springs 16 after the feed-clutches 29 (see Fig. 2) have been withdrawn, so that the carbons are free to feed by gravity. 120

The striker-spindle 23 is operated in conjunction with the feed-clutches 29 in a well-known manner by a solenoid and core.

It will be understood that when the pawl 13 is retracted from the position shown in 130

Fig. 5 to that shown in Fig. 6 the carbon 21 will be free to fall upon the flange 11 of the carbon-holder 1, as the motion of the magazine cannot then be reversed, owing to the 5 carbon 20 being partly in the holder 1 and partly in the magazine-chamber 8.

As shown, two solenoids 30 are preferably employed, their respective cores 31 being secured to a cross-bar 32, connected by an adjustable rod 33 to a pivot 34 next the outer end of one arm 35 of a bell-crank lever carried by a horizontal pivot 36, secured in a snug cast on one of the carbon-holders 1. The other arm 37 of the aforesaid bell-crank 15 is connected by a horizontal pivot 38 to one end of a link 39, the other end of which is connected by a vertical pivot 40 to a crank 41, secured on the striker-spindle 23.

The aforesaid pivot 38 or the boss at that 20 end of the link 39 is arranged to project and to come into contact with the carbon-holder 1, so as to form a stop for the striking-gear and also for the magazine-rotating device. The feed-clutches 29 are formed at the end of 25 one arm 42 of two bell-crank levers horizontally pivoted at 43 in snugs cast on the carbon-holder 1, the other ends 44 of the said bell-crank levers being provided with horizontal pivots 45, which are connected to horizontal pivots 60, provided on each side of the crank-arm 35 at a point intermediate between the pivot 36 and the pivot 34, by connecting-links 46, provided at their upper ends with adjusting-screws 47, which afford a certain 30 amount of lost motion to permit the point of the striker to arrive in position before the clutches 29 are released.

Pressure is put upon the feeding-clutches 40 29 by springs 48, attached at their upper ends to pins 49, secured to the carbon-holder 1, and at their lower ends to an extension-bar 50, secured to the crank-arm 44.

It is obvious that the pawl 13 may be replaced by a disk having a slot sufficiently 45 large to clear two carbons—for instance, 20 and 21, Fig. 6—in which case the supplementary table 12 or a portion thereof would not be required and, further, that the spring-pawl may operate the magazine directly by contact—for example, with the tubes 9 or a series of projections on the magazines—in which case the carbons would normally rest on the flange 11 of the carbon-holder 1.

Referring now to Fig. 7, in which the electrical circuits of the lamp are illustrated, the series coils 30 for controlling the feed of the mechanism are connected as a shunt to the arc, the circuits being completed through contacts 56 57, contact 57 being carried by the 55 armature 55 of the electromagnet 54, which is also shunt-wound. The numeral 51 indicates the usual control-magnet, and 58 represents the substitute resistance.

The operation of the lamp is as follows:

When the current is switched on, sufficient 65 current traverses the coil of the magnet 54 to cause its armature 55 to be attracted, and thereby to complete the circuit of the series coils 30, which thus become energized and attract the cores 31, by which means the striker 70 75 80 85 90 95 100 105 110 115 120 125 130 135 140 145 150 155 160 165 170 175 180 185 190 195 200 205 210 215 220 225 230 said core being so related to the said spring as to compress the latter when the said magnet is energized.

2. An electric-arc lamp having electrodes feeding by gravity upon the release of a clutch operated by electromagnetic means, the coils for operating the feeding mechanism being cut out by a shunt-wound electromagnet when the arc is struck or when the arc does not exceed the normal length, the shunt-wound mag-

net having an armature, by means of which the circuit of the electrode-feeding coils is both opened and closed.

Signed at London, in the county of Middlesex, England, this 27th day of January, A. D. 1904.

WILLIAM REGINALD RIDINGS.
